W. K. HOWE.

ELECTRIC INTERLOCKING PROTECTIVE DEVICE,
APPLICATION FILED OCT. 7, 1911.

1,163,153.

Patented Dec. 7, 1915.

UNITED STATES PATENT OFFICE.

WINTHROP K. HOWE, OF ROCHESTER, NEW YORK, ASSIGNOR TO GENERAL RAILWAY SIGNAL COMPANY, OF GATES, NEW YORK, A CORPORATION OF NEW YORK.

ELECTRIC INTERLOCKING PROTECTIVE DEVICE.

1,163,153.

Specification of Letters Patent.

Patented Dec. 7, 1915.

Application filed October 7, 1911. Serial No. 653,354.

To all whom it may concern:

Be it known that I, WINTHROP K. HOWE, a citizen of the United States, and resident of the city of Rochester, in the county of 5 Monroe and State of New York, have invented a new and useful Electric Interlocking Protective Device, of which the following is a specification.

This invention relates to electric interlocking and particularly to a protective device therefor.

One of the objects of this invention is a mode of construction and connection of a protective device such that only the function 15 which is affected by a cross or foreign current will be rendered inoperative.

Other objects and advantages of the invention will appear as the description progresses.

20 In the single figure of the drawing accompanying this specification, wherein applicant has illustrated a preferred form of his invention, similar reference characters refer to like parts.

25 1 designates a reciprocating lever such as is used in electric interlocking systems. This lever is adapted to slide in guides and to have four critical positions, to-wit: a normal position, a reverse position, a normal indication position, and a reverse indication position and is adapted to be moved to these 30 different positions by means of the handle 2.

The position in which the lever is shown is what is called the normal position. Upon 35 being moved in the direction of the arrow *a*, the lever through the projection 3, acting on the end 4 of a latch 5, causes the other end 6 of the latch 5 to be raised so as to lie in the path of the projection 7 upon the lever 1, so that the lever 1 cannot be moved beyond 40 a position in which the end 6 of the latch 5 and the projection 7 of the lever 1 are in contact. As soon as the latch 5 is raised by the action of the lever, it is held 45 in such position by means of the dog 8, which swings upon the pivot pin as shown and is pushed under the end of the latch by means of cam 9, which is rotated on its pivot as shown by the engagement of the 50 projection 7 on the lever 1 with the bifurcated upper end of the cam. When the lever has been stopped in its movement to the reverse position by the latch 5, it is then in what is called its reverse indication posi-

tion and is allowed to be moved therefrom 55 to the full reverse position only by the energization of the electro-magnet 10 which raises the armature 11 thereby causing the rod 12, attached thereto, to strike the lower limb of the dog 8 and force the upper limb 60 from beneath the end 6 of the latch 5. As soon as the dog 8 has been removed from beneath the latch 5, the lever may be moved to the full reverse position. If the lever is moved from the reverse position to the normal 65 position, it is stopped at the normal indication position by the end 6 of the latch 5 engaging with the projection 7¹ of the lever as the latch 5 has its end 6 raised into the path of such projection by the projection 3 upon the lever 1 and the dog 8 is moved underneath the latch 5 by the movement of the cam 9 caused by the movement 70 of the lever 1 toward the normal position, causing the projection 7 to engage with the 75 bifurcated end of the cam 9. The lever is released from the normal indication position by the raising of the armature 11 in the same way that it is released from the reverse indication position. 80

All of the above mechanism is fully shown, described and claimed in the patent granted to John D. Taylor, February 16th, 1904, #752,127, which also shows, describes and claims the safety magnet 13. 85

The indication selector 14 is fully shown, described and claimed in the patent to John D. Taylor, granted October 2nd, 1906, #832,175.

The lever 1 has the rod 15 attached thereto which bears upon its outer end the cross arm 16 which carries on either end the metallic brushes 17 and 18. In the normal position of the lever as shown, the metallic brushes 17 and 18 are adapted to contact 90 with and make connection between springs 19, 20, 21 and 22, but when the lever is in the reverse position, brush 17 is adapted to contact with and make connection between springs 23 and 24 and brush 18 is adapted 95 to contact with and make connection between springs 25 and 26. 100

S, designates the motor and associated apparatus for moving a switch, the same being fully shown and described in the patent to John D. Taylor, granted September 26th, 1905, #800,246. 105

27 designates an arm pivoted at 28 and

being constantly acted upon by weight 29, to move it in the direction of the arrow *b*. The upper end of the arm is pivoted at 30 to the armature 31, which is pivoted at 32 and 5 is adapted to coöperate with the electro-magnet 33, having the coils of conducting wire 34 and 35 thereon; 36 designates a bridge of conducting material which is attached to arm 27 by means of the insulating 10 post 37 and is adapted to contact with metallic pieces 38 and 39 when in the position shown and to so complete a path for electric current from one to the other. The pivoted member 27 bears the outstanding arm 40 15 which is adapted to abut against the end of the armature 42 when the armature is in the raised position and to thereby prevent a movement of the arm 27 upon its pivot to the position shown after having been moved 20 by weight 29 in the direction of the arrow *b*. The armature 42 is governed by the electro-magnet having a coil 43.

Upon the movement of the lever 1 to the reverse indication position, current flows 25 from the battery 45 through wires 46 and 47, safety magnet 13, wire 48, wire 49, left hand coil of indication selector 14, wire 50, spring 26, brush 18, spring 25, wires 51 and 52, spring 53, movable contact bar 54, spring 55, 30 wire 56, brush 57, armature 58, brush 59, wire 60, spring 61, movable contact bar 62, spring 63, wire 64, field 65, wire 66, field 67, wires 68 and 69, field 70, wire 71, field 72, wires 73, 74 and 75, contact 39, bridging 35 conductor 36, contact 38, wire 76, to the negative terminal of the battery 45, thus completing the circuit. The current flowing in the above traced path holds the armature 11 down upon the poles of the safety magnet 40 and also energizes the left hand coil upon the indication selector 14, thereby moving the armature 77 upon its pivot so that it connects 78 and 79. It also causes an energization of the switch throwing motor at S, 45 thereby causing the same to revolve and throw a switch which may be connected thereto and moves the cross contacting bars 54 and 62 so as to bridge springs 79 and 80 and 81 and 82 respectively, as fully shown, 50 described and claimed in the patent to John D. Taylor, granted August 27th, 1901, #681,589. After the switch is thrown the motor armature is allowed to rotate free from the connecting mechanism as explained 55 in the last mentioned patent, thereby generating an indication current which flows from brush 57 through wires 56 and 83, spring 81, movable contact 62, which has been moved, spring 82, wires 84 and 64, field 65, wire 66, field 67, wire 68, wire 69, field 70, wire 71, field 72, wires 73, 74 and 85, coil 34, 60 wire 86, indication magnet 10, wire 87, contact strip 78, armature 77, contact strip 79, wire 88, contact spring 24, brush 17, contact spring 23, wires 89 and 90, contact spring 65

79, movable contact 54, which has been moved, and wires 91 and 60 to the other brush 59 of the motor, thereby completing the circuit, in which a current flows of sufficient strength to lift the armature 11 and 70 cause the rod 12 attached thereto to strike the lower limb of the dog 8, and release the latch 5, so that the full stroke of the lever may be completed.

The operation of the switch from reverse 75 to normal is similar to the operation of the switch from normal to reverse and can easily be traced out by one familiar with the art and is furthermore fully shown and described in the patent to Taylor, #800,246 80 granted September 26th, 1905, in which the functions of electro-magnets 92, 93, 94 and 95 are fully explained and in which also the function of the rotary circuit controller 96 is also explained.

Irrespective of the direction of movement of the motor in moving a switch, the indication current always flows in wire 74 in the direction of the arrow *c*, so that the indication current circulates about the electro-magnet 33 counter-clockwise, and in so doing aids the current flowing in coil 35 to hold the armature 31 in place. The circuit for coil 35 is as follows: positive side of battery 45, wire 46, wire 97, coil 35, wire 98, 95 contact 38 and wire 76 back to the negative terminal of the battery. As such circuit is always closed, the amount of current flowing therein may be easily regulated to an economical value by the adjustment of the 100 resistance of coil 35. It will be noted that the current flowing through the coil 35, also flows about the core of the electromagnet 33 in a counter-clockwise direction, so that both coils 33 and 35 act to hold armature 31 in 105 place when indication current is flowing in coil 34 in the proper direction.

No system of electric interlocking is safe unless means are provided to prevent the movement of a switch or signal out of correspondence with the controlling lever and in the past many devices for such purpose have been devised, but all of such devices have been heretofore of such a nature that a cross or the entrance of foreign current 110 into the system caused current to be cut off from all functions. This is in some cases undesirable, especially in a very large interlocking plant where one section of the tracks controlled from the interlocking tower may 115 operate practically independently of another section of tracks controlled from the interlocking tower, so applicant has devised a system in which the only function cut off from the main source of current is the function likely to be affected by the cross or foreign current. In case a wire carrying current were crossed with wire 52 with the lever 1 in the position shown, current would 120 be fed to the motor to rotate it so as to place 125 wire 52 with the lever 1 in the position shown, current would 130

the switch connected thereto in a position out of correspondence with the controlling lever 1. Heretofore such a cross has resulted in the opening of the circuit to the 5 battery so that no function in that section could be operated, but in the system herein shown, only that function immediately concerned would be affected. The current which would flow in wire 52 to contact 10 spring 19 and then through brush 17, contact spring 20, wire 99, contact 100, armature 77, contact 78, wire 87, indication magnet 10, wire 86, coil 34, wires 85 and 75 to contact 39 and bridge 36, contact 38, and 15 wire 76 to the negative terminal of the battery. This current flows through the coil 34 in a direction reverse to that in which the regular indication current flows, therefore the flux generated by coil 35 would be neutralized and the armature 31 through the arm 27 and the weight 29 would be drawn away from the pole of the electro-magnet 33 thereby allowing the bridge 36 to break contact with contacts 38 and 39 leaving the 20 winding 43 of high resistance bridged across wires 75 and 76, consequently the path for the current back to the negative terminal of the battery would then be of such high resistance that sufficient current could not flow 25 from wire 52 through the motor at S and back to the negative terminal of the battery to operate the motor, therefore, the switch would not be moved by wire carrying current making a cross with the wire 52.

30 35 When bridge 36 moved from in contact with contacts 38 and 39 a path of very high resistance from wires 75 to wire 76 was formed through the coil 43. This path allows sufficient current to flow therein to 30 energize the core upon which the coil 43 is wound sufficiently to raise the armature 42, but does not allow sufficient current to flow through the motor to cause it to revolve. As soon as the armature 42 is raised, the 45 armature 27 cannot be returned to normal position as shown in the figure, for the arm 40 would contact with the end of armature 42 and thus prevent such movement. It is to be further observed that just as long as 50 a wire carrying current remains in contact with wire 52 a current will flow through the coil 43, so that it is impossible to return the arm 27 to its normal position, thus bridging contacts 38 and 39 until all current through 55 the coil 43 has ceased and the armature 42 has dropped to the normal position as shown in the figure. This mode of operation is for the purpose of preventing an operator from moving the arm 27 into its normal position 60 before the cross has been removed and then attempting to operate the switch controlled by the wires which are crossed. It is also to be observed that as long as the cross remains, current will flow through coil 34 in the reverse direction, so that even if it were

possible to raise the arm 27 to its normal position before the cross were removed, it would be necessary to hold it there manually while operating the lever 1 which is generally prevented by placing the device, including the arm 27, at some distance from the lever 1.

Although applicant has herein shown and described one operated function only and one means for operating one function, it is 75 to be understood that both the means for operating and the operated functions will, in an interlocking plant, be duplicated to any extent desired.

It must now be understood that applicant 80 has devised a system of protection which is directed merely to the particular function which is affected and concerns in no way the other functions which may be associated with it. It is to be further observed that 85 this method of protection requires that a separate wire be extended from each switch or signal movement to the interlocking tower at which the lever 1 and the device including the arm 27 is placed, but by reason of the superior advantages of such a 90 method of protection, the added expense is immaterial.

Having particularly described the construction and connection of one embodiment 95 of my invention and explained the operation and principle thereof, what I claim as new and desire to protect by Letters Patent, is:

1. In an electric interlocking system, a source of current, a signaling device, circuit controllers, a lever for moving the circuit controllers, connections from the source of current to the circuit controllers, connections from the circuit controllers to the signaling device, a return connection from the 100 signaling device to the source of current, and means interposed in said return connection to break the normal continuity of the same when current flows to said second mentioned connections from an improper source, and 105 means responsive to such flow of current for holding said means in its operated position until such flow of current ceases.

2. In an electric interlocking system; a source of current; circuit controllers; a signaling device; a return path for current from the signaling device to the source of current; an electrical connection from the source of current to the circuit controllers; 115 electrical connections from the circuit controllers to the signaling device; means for moving the circuit controllers for connecting the source of current with the signaling device; means interposed in the return path for breaking the continuity of the same if 120 current is supplied to that one of the connections from the circuit controller to the signaling device which the circuit controller is not in a position to supply current to; and means responsive to such current for 125 130

positively preventing manual restoring of such means to a position to close said return path while such current is supplied.

3. In an electric interlocking system: a source of current; a signaling device; a return connection from the signaling device to the source of current; a connection from the source of current to the signaling device; a movable circuit controller interposed in said last mentioned connection; means for breaking the continuity of the return connection; and means for locking said circuit controller open and thereby retaining the continuity broken against manual completion until the last named means are inactive to break the continuity of the return connection.

4. In an electric interlocking system: a source of current; a signaling device having a plurality of terminals and adapted to generate a current; a return connection from the signaling device to the source of current; circuit controllers comprising fixed contacts and movable bridges; a plurality of conductors, each conductor connected at one end to a separate terminal of the signaling device and at and near the other to a plurality of separate fixed contacts of the circuit controllers; an indication magnet having two terminals; means connecting one terminal of the indication magnet to a plurality of fixed contacts of the circuit controllers; a connection from the other terminal of the indication magnet to the return connection having a coil interposed therein; a core for said coil; another coil on said core normally energized from the source of current; means governed by said core for preserving the continuity of the return connection when current generated by the signaling device flows through the first mentioned coil, and when the current flows through the second mentioned coil from the source, said means acting to break said return connection when current flows from the indication magnet through the first mentioned coil to the return connection; means energized upon said last mentioned flow for preventing manual closing of the return connection until the flow of current from the indication magnet to the return ceases.

5. In an electric interlocking system: a function; a source of current; operating wires; means for connecting the source of current through the operating wires with the function; a return connection from the function to the source of current; a circuit controller included in said return connection; and means for opening said circuit controller when current from the source flows improperly to an operating wire; a device for holding said circuit controller open; and means set into operation by such flow of improper current for operating said device to prevent said circuit controller from be-

ing restored to its normal closed position until such improper flow of current ceases.

6. In an electric interlocking system, in combination: a source of current; an electrically operated function; a return connection from said function to said source of current; a circuit controlling lever for governing the movements of said function; a circuit which is closed when said lever and said function are at rest; electromagnetic means operated to break said return connection when current from said source flows through said circuit; and means responsive to said flow of current for holding said electromagnetic means in its operated position until such flow of current ceases.

7. In an electric interlocking system, in combination: a source of current; an electrically operated function; operating wires for leading current from said source to said function; a circuit controlling lever for governing the connection between said operating wires and said source and operable to govern the movements of said function; a return connection from said function to said source; electromagnetic means for automatically breaking said return connection when current from said source flows in an operating wire which is disconnected from said source by said lever; and means set into operation by such flow of current for retaining said electromagnetic means in its operated position and thereby positively preventing the continuity of said return connection from being established at any time until such flow of current ceases.

8. In an electric interlocking system, in combination: a source of current; an electrically operated function; a return connection from said function to said source; a conductor connected to said return connection; operating wires for carrying current from said source to said function; a circuit controlling lever arranged to connect said operating wires alternately one at a time to said source of current and to said conductor; a circuit controller interposed in said return connection; electromagnetic means interposed in said conductor and operated by a flow of current therein in a certain direction to open said circuit controller; and means for holding said circuit controller open until such flow of current ceases.

9. A protective device for electric interlocking systems, comprising a circuit controller; electromagnetic means for controlling said circuit controller; a circuit for said means, said means being operated by a flow of current in said circuit in a certain direction, and means for holding said circuit controller open until the flow of current in said circuit in said direction ceases.

10. A protective device for electric interlocking systems, comprising a circuit controller; means tending to open said circuit

controller; electromagnetic means responsive to a flow of current in a certain direction for holding said circuit controller closed and operating to permit said circuit controller to open when the flow of current is reversed; a high resistance path across the contacts of said circuit controller; and means operated by said flow of current in said path for holding said circuit controller open.

11. In an electric interlocking system, in combination: a circuit; a normally closed

circuit controller included in said circuit; electromagnetic means operated by a flow of current in said circuit in a certain direction for opening said circuit controller; and means operated so long as said flow of current exists for holding said circuit controller open.
